UNITED STATES PATENT OFFICE.

TROY ALMOND LEONARD BOWEN, OF TULSA, OKLAHOMA.

DERRICK.

Application filed February 24, 1926. Serial No. 90,312.

The invention relates to derricks, and has for its object to provide an oil well derrick or rig, in which the parts are made from steel and the rig supported on concrete footers, thereby providing a rigid structure which may be easily taken down, and moved from point to point as desired and at the same time a positive operating device is provided as the steel parts will 10 not warp or twist incident to weather conditions, and at the same time the life of the rig will be extended.

A further object is to form the swing beam or lever from opposed channels having their flanges extending towards each other and connected together by bars in zig zag relation thereby forming a lever which is rigid, formed from metal, and one which is thoroughly trussed and braced.

20 A further object is to provide the lower end of the swing lever with a block having its opposite sides disposed within the channel members, a bearing member carried by the block and a base plate anchored to one 25 of the concrete footers and having a bearing therein for the bearing member carried by the block.

A further object is to provide anchoring bolts in the footer, which bolts extend upwardly through elongated alined slots in the base plate, and are provided with notched washers cooperating with transversely disposed ribs of the plate for holding the plate against lateral displacement and in adjusted 35 positions.

With the above and other objects in view the invention resides in the combination and arrangement of parts as hereinafter shown in the drawings, described and claimed, it being understood that changes in the precise embodiment of the invention may be made within the scope of what is claimed without departing from the spirit of the invention.

45 In the drawing:—

Figure 1 is a side elevation of the rig.

Figure 2 is a top plan view of the rig.

Figure 3 is a side elevation of the swing lever.

50 Figure 4 is a top plan view of the base plate.

Figure 5 is a side elevation of the engine supporting bars.

55 Referring to the drawings, the numeral 1 designates the tower which is formed from metal and the angle iron legs 2 of which

rest on the concrete footers 3, therefore it will be seen that the tower is positively seated on a rigid foundation, and the same may be disassembled for moving from place to place when desired. Disposed adjacent one side of the tower 1 is a Sampson post 4, which is vertically disposed and which Sampson post is mounted on a concrete footer 5. The Sampson post 4 is braced by brace bars 6, which thoroughly brace the same. The Sampson post is built up from channel iron for rendering the same rigid at the same time a permanent structure. Pivots connected at 7 to the upper end 70 of the Sampson post 4 is a walking beam 8, to one end of which is connected the pump rod 9 in the usual manner. Disposed rearwardly of the Sampson post 4 is a jack post 10, which is also formed from metal and mounted on a concrete footer 11. Rotatably mounted in a bearing carried by the upper end of the jack post 10 is a transversely disposed shaft 12, which shaft is provided with a crank 13, to which is connected an upwardly extending connecting rod 14, the upper end of which pivotally engages one end of the walking beam 8, and it will be seen that when the shaft 12 is rotated, the walking beam 8 will be oscillated 85 on its pivotal point 7. Mounted on the shaft 12 is a drive pulley 15, around which an endless belt 16 extends. The belt 16 extends over a pulley 17 carried by an engine 18, which is mounted on spaced parallel bars 19 which are clamped by means of clamps 20 to eye beams 21 which are in turn mounted on footers 22, therefore it will be seen that the engine 18 is rigidly mounted. The engine 18 may be of any type desired, that is it may be a gas engine or steam engine, and applicant makes no claim to any specific type of engine. Mounted on the transversely disposed shaft 12 is a pulley 23, and extending around said pulley and the wheel 24 is a crossed drive belt 25 which operates in the usual manner. The sand reel 26 is of a conventional construction, and is mounted on a transversely disposed shaft 27 and is driven by means of a sprocket 28 carried by the shaft 27, and over which sprocket a sprocket chain 29 extends. The sprocket chain 29 extends over a sprocket 30 carried by the transversely disposed shaft 12, therefore it will be seen that during the rotation of the shaft 12, the sand reel 26 will also operate.

105

110

115

The jack post 10 is braced by means of brace bars 31, and which bars are formed from metal. Disposed outwardly from the jack post 10 is a tail post 32 which is built up from channel iron and which tail post is mounted on a concrete base 33. The tail post supports one end of a transversely disposed shaft 34, which shaft is provided with drums 35 in the usual construction. Also mounted on the transversely disposed shaft 34 is a pulley 35, which when the shaft is swung inwardly at one of its ends in the direction of the arrow *a*, and engages the periphery of the pulley 15 whereby the shaft 34 and the drums 35 are rotated. The movable end of the shaft 34 is mounted in a bearing block 36 of the swing lever 37, and which spring lever is formed from opposed channel members 38 which are connected together by zig zag arranged bars 39. The bars 39 and channel members 38 are formed from metal and the bars 39 are connected to the flanges 40 thereof, and the bearing block 36 is disposed between the channels 38 and are connected to the flanges 40 by means of rivets 42. Secured within the lower ends of the channeled members 38 is a block 43, the lower end of which is provided with a bearing member 45, which is rockably mounted in a semi circular shaped bearing 45 of a plate 46 which engages the upper side of a concrete base 47. It is necessary at times to adjust the swing lever towards and away from the tower 1 for properly positioning the same whereby the pulley 35 will properly engage the pulley 15. To adjust the base plate 46 and at the same time positively hold the base plate 46 in any adjusted position, anchoring bolts 48 are provided, which anchoring bolts extend upwardly through elongated slots 49 in the base plate 46 and are provided with toothed washers 50, which cooperate with the transversely disposed ribs 51 carried by the upper side of the plate, and which washers are held in close interengagement with the ribs 51 of the plate 46 by means of nut 52. It will be seen when it is necessary to adjust the swing lever it will only be necessary to loosen the nuts 52 and move the plate inwardly or outwardly as desired to the desired position and after which the nut can be tightened. Pivotaly connected at 53 to the upper end of the swing lever is a forwardly extending connecting rod 54 which has its forward end connected to a lever 55, which is adapted to be manipulated by the operator for moving the drum 35 into and out of driving engagement with the pulley 15.

From the above it will be seen that a derrick rig is provided, which is simple in construction, all the parts formed from metal and mounted on concrete bases, thereby

providing a strong rigid structure, which will last indefinitely, and it will also be seen that the use of sills is obviated and timbers which rapidly deteriorate and which easily warp and twist incident to weather conditions and use.

The invention having been set forth what is claimed as new and useful is:—

1. The combination with an oil well drill member, of an adjustable mounting for said member, said member comprising a horizontally disposed plate, a foundation for said plate, a pivotal connection between the oil well drill member and the plate, bolts extending upwardly from the foundation through elongated slots in the plate, said plate being provided with transversely disposed ribs, washers surrounding the bolts above the plate, transversely disposed ribs carried by said washers and interengaging the transversely disposed ribs of the plate and nuts threaded on said bolts and engaging the upper side of the washers.

2. The combination with an oil well drill rig swing lever, of a mounting for said lever, said mounting comprising a horizontally disposed plate, a foundation for said plate, pivotal connections between the lever and the plate, bolts carried by the foundation and extending upwardly through elongated aligned slots in the plate, transversely disposed ribs carried by the plate, toothed washers carried by the bolts and cooperating with the ribs of the plate and nuts carried by said bolts and cooperating with the toothed washers.

3. The combination with an oil drill rig, of a swing lever therefor, said swing lever being substantially vertically disposed, a bearing plate beneath said swing lever, said plate being disposed and laterally movable on a foundation, of bolts carried by the foundation and extending through aligned slots in the plate, toothed washers carried by the bolts, said toothed washers cooperating with teeth carried by the plate and nuts threaded on the bolts.

4. A swing lever for oil well drilling rigs comprising spaced channeled members, the flanges of the channeled members extending towards each other, brace bars connecting the flanges of the channeled members, a bearing between the channeled members and secured to the flanges thereof, a bearing block between the channeled members adjacent their lower ends and secured thereto, a bearing member carried by said last named block and a supporting bearing member cooperating with the last named bearing member.

In testimony whereof I hereunto affix my signature.

TROY ALMOND LEONARD BOWEN.
